(57) **CLAIM**

The ornamental design for a multi-media monitor, as shown and described.

DESCRIPTION

FIG. 1 is a front right side perspective view of a multi-media monitor in accordance with the new design;

FIG. 2 is a rear right side perspective view thereof;

FIG. 3 is a front elevational view thereof;

FIG. 4 is a rear elevational view thereof;

FIG. 5 is an enlarged right side elevational view thereof, the left side elevational view being a mirror image thereof;

FIG. 6 is a top plan view thereof; and,

FIG. 7 is a bottom plan view thereof.

The broken lines shown in FIGS. 1-7 are for the purpose of illustrating portions of the multi-media monitor that form no part of the claimed design.
